UNITED STATES PATENT OFFICE.

ALBERT D. PURTLE, OF MARIETTA, OHIO.

BRASS-LINER STUFFING-BOX HEAD.

Application filed May 7, 1921. Serial No. 467,667.

To all whom it may concern:

Be it known that I, ALBERT D. PURTLE, a citizen of the United States, residing at Marietta, in the county of Washington and State of Ohio, have invented a new and useful Brass-Liner Stuffing-Box Head, of which the following is a specification.

This invention relates to pump constructions, and more particularly to brass liner stuffing box heads, it being the primary object of the invention to provide novel means for insuring a fluid-tight connection between the head and liner to eliminate wasting of the oil during the pumping operation.

15 A further object of the invention is to provide a one-piece head presenting a single packing point thereby reducing the packing necessary to provide a fluid-tight joint, to a minimum.

20 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

25 Referring to the drawing:—

Figure 1 is a longitudinal sectional view of a stuffing box head constructed in accordance with the present invention.

30 Figure 2 is a sectional view taken on line 2—2 of Figure 1.

35 Referring to the drawing in detail, the reference character 5 designates the stuffing box head which is provided with a lateral opening to accommodate the screw 6 that contacts with the polished rod 7 of the pump construction for securing the polished rod in predetermined positions of adjustment.

40 The head 5 is provided with an opening extending from the lower end thereof into the body portion, terminating at a point substantially intermediate the ends of the head, the opening being for the purpose of accommodating the packing 8 and the upper end of the liner tube 9 in which the polished rod 7 is positioned.

45 As shown, the upper end of the liner tube 9 is flared outwardly as at 10 providing a

flange to restrict movement of the tube 9 with respect to the rod 7, when the same has been properly positioned. The inner 55 wall of the opening formed in the head 5 is threaded to accommodate the threads of the follower 11 which, when the same is positioned within the opening of the head, forces the packing 8 into close engagement 60 with the walls of the opening and the flared portion 10 of the tube 9.

From the foregoing it will be seen that due to the construction as described, a fluid-tight connection between the polished rod 7 and the liner tube is provided at all times. In assembling a structure of this character, the head 5 is properly positioned on the rod 7, whereupon packing is positioned within the opening of the head. The liner tube is now 70 brought to a position where the flared extremity thereof contacts with the packing, and the packing is further positioned within the opening to contact with the opposite side of the flange 10. The follower 11 is now positioned within the opening and rotated to force the packing into close engagement with the elements of the device.

Having thus described the invention, what is claimed as new is:—

50 A stuffing box head having an opening formed therein, a polished rod operating through the opening, a liner tube embracing a portion of the polished rod and having one end thereof disposed within the opening, packing material within the opening disposed around the rod and contacting therewith, the packing material being positioned above the liner, means formed at the upper end of the liner tube and embedded in the packing material for restricting movement of the liner tube with respect to the polished rod, packing material positioned below the upper end of the liner and contacting therewith, and means for securing the packing 90 within the head.

55 In testimony that I claim the foregoing as my own, I have hereto affixed my signature in the presence of two witnesses.

ALBERT D. PURTLE.
